DISPENSING HEAD FOR BEER AND THE LIKE

Bryn H. Nissen, 5875 Walsh, St. Louis, Mo.

Filed Oct. 14, 1960, Ser. No. 62,493

Term of patent 14 years

(Cl. D2—3)

FIG.4

FIG. 1 is a front elevational view of a dispensing head for beer and the like showing my new design.

FIG. 2 is a side elevational view thereof.

FIG. 3 is a sectional view taken along the line 3—3 of FIG. 1, and

FIG. 4 is a sectional view taken along the line 4—4 of FIG. 1.

The dominant features of my design reside in the portions shown in full lines.

I claim:

The ornamental design for a dispensing head for beer and the like, substantially as shown and described.
